UNITED STATES PATENT OFFICE.

WILLIAM CLARE MACMILLEN, OF ROCHESTER, PENNSYLVANIA.

DESIGN FOR A NAME PLATE FOR GASOLINE-DISPENSING APPARATUS.

Application filed January 4, 1922. Serial No. 35. Term of patent 3½ years.

To all whom it may concern:

Be it known that I, WILLIAM C. MACMILLEN, a citizen of the United States, residing at Rochester, in the county of Beaver and State of Pennsylvania, have invented a new, original, and ornamental Design for a Name Plate for Gasoline-Dispensing Apparatus, of which the following is a specification, reference being had to the accompanying drawing forming part thereof.

The figure is a front elevation of a name plate for gasoline dispensing apparatus showing my design.

I claim—

The ornamental design for a name plate for gasoline dispensing apparatus, as shown. In testimony whereof I affix my signature.

WILLIAM CLARE MACMILLEN.
